US0D1038114S

(12) **United States Design Patent** (10) **Patent No.:** **US D1,038,114 S**
(45) **Date of Patent:** **** Aug. 6, 2024**

(54) **NOTEBOOK COMPUTER**

(71) Applicant: **Acer Incorporated**, New Taipei (TW)

(72) Inventors: **Wei-Chang Chen**, New Taipei (TW);
Jung-Wei Tsao, New Taipei (TW);
Chun-Te Lin, New Taipei (TW);
Ker-Wei Lin, New Taipei (TW)

(73) Assignee: **Acer Incorporated**, New Taipei (TW)

(**) Term: **15 Years**

(21) Appl. No.: **29/885,188**

(22) Filed: **Feb. 21, 2023**

(30) **Foreign Application Priority Data**

Aug. 24, 2022 (TW) 111304213

(51) **LOC (14) Cl.** **14-02**

(52) **U.S. Cl.**

USPC **D14/315**; D14/439

(57) **CLAIM**

The ornamental design for a notebook computer, as shown and described.

DESCRIPTION

FIG. 1 is a perspective view of a notebook computer showing our new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a perspective view thereof showing the notebook computer in an alternate position;

FIG. 10 is another perspective view thereof showing the notebook computer in an alternate position;

FIG. 11 is an enlarged view of the portion, labeled '11' of FIG. 9; and,

FIG. 12 is an enlarged view of the portion, labeled '12' of FIG. 10.

The even-dashed broken lines shown in the drawings illustrate portions of the notebook computer that form no part of the claimed design. The dot-dash broken line rectangles depict the limits of the enlarged views and form no part of the claimed design.

1 Claim, 8 Drawing Sheets
